CYLINDER

Ralph Miller, Easton, Pa., assignor to Ingersoll-Rand Company, Jersey City, N. J., a corporation of New Jersey

Application March 17, 1931. Serial No. 523,229

6 Claims. (Cl. 123—173)

This invention relates to engines, but more particularly to a cylinder for engines employing water jackets as a means for maintaining the temperature of the cylinder at a practical value.

5 One object of the invention is to assure proper temperature of the cylinder.

Another object is to maintain the weight of the cylinder at a minimum.

Other objects are to enable the use of tubing 10 for the cylinder and to avoid the subjection of the water jacket to stresses incident to expansion and contraction of the cylinder in a longitudinal direction.

Other objects will be in part obvious and in 15 part pointed out hereinafter.

The accompanying drawing forming part of the specification is a sectional elevation of so much of an engine as will serve to illustrate the invention.

20 Referring more particularly to the drawing, A designates generally an engine comprising a base or bed plate B, a cylinder C supported by the bed plate B, and a head D seated on the end of the cylinder C and which may be secured thereto 25 by means of bolts E.

The engine A may be considered as being of the internal combustion type and the head D is accordingly provided with a combustion chamber F of known design into which the fuel may be 30 injected or otherwise introduced, and wherein such fuel may be ignited for actuating a piston G reciprocable within the cylinder C.

The cylinder C, constructed in accordance with the practice of the invention, comprises a tube 35 of which the wall H is of substantially uniform thickness throughout. The upper or outer end of the cylinder C may, however, be slightly enlarged or upset to form thereon a raised portion J and in the periphery of which are formed 40 threads K for cooperation with threads L carried by a lateral flange O, and which flange, together with the end of the cylinder C, supports the weight of the head D. The said flange O may also, as shown, serve as an anchorage for the 45 bolt E.

Near its lowermost end the cylinder C is provided with a second threaded portion P to accommodate a flange Q which acts as a seating surface for the cylinder C, said flange being seated upon the bed plate B to which it may be secured in any suitable manner, as for instance by bolts R.

In order to assure tight connections between the cylinder and the flanges O and Q the said 50 flanges are applied to the cylinder in a heated

condition and permitted to cool in the assembled position to effect a shrinkage fit between these elements.

Arranged exteriorly of the cylinder C is a water jacket S carrying at its upper end a flange T through which extend bolts U for securing that end of the water jacket to the flange O. In the opposite end of the water jacket S is a bore V through which the cylinder C extends and with which the outer surface of the cylinder may be 65 in body contact.

Preferably, packing material W is disposed in the water jacket S adjacent the bore V to assure against leakage of cooling water from the water jacket at this point. In structures wherein the 70 walls of the water jacket S are of extremely small thickness the free or lowermost end of the water jacket may be additionally reinforced by shrinking or clamping thereon a band or ring X.

In accordance with the usual practice, the 75 water jacket S is provided near its lowermost end, that is, at a point adjacent the bore V with an inlet opening Y through which cooling water may be introduced into the water jacket. At or near the upper end of the water jacket is an outlet 80 opening Z through which the cooling water may escape from the water jacket.

In order to assure a desirable turbulence in and a maximum cooling effect of the water during 85 its passage through the water jacket S, said water jacket is provided on its inner surface with a plurality of internal flanges, two in this instance, and which are designated by b and c, to divide the interior of the water jacket into compartments d, 90 e and f. The inner surfaces of the flanges b and c may be in body contact with the outer surface of the cylinder C and said flanges b and c are provided with passages g and h respectively through 95 which the water may flow from one compartment to another, the passages g and h being preferably located diametrically opposite to each other.

In practice, and with the parts assembled in the manner described, water flowing from the inlet opening Y and to the lowermost compartment d of the water jacket will flow in opposite 100 directions around the cylinder C, thence through the passage g into the compartment e. Therein the water will also flow in opposite directions around the cylinder C but in a direction counter to its course through the compartment d. From the compartment d the water flows through the passage h into the compartment f wherein it will follow a course similar to that through the compartment d and will then flow from the water jacket through the outlet opening Z. During its 110

course through the water jacket the water will thus be brought into contact with a large area of the cylinder C and the temperature of the cylinder may therefore be maintained at a low value 5 and with the use of a minimum quantity of water.

Constructed as described the cylinder, together with the water jacket, may be of extremely light weight and the cylinder may be constructed of standard tubing of high wear and strain resisting qualities. Another advantage derived 10 from this mode of construction is that the cylinder and the water jacket may expand in accordance with their respective temperatures without subjecting each other to unnecessary strains.

15 I claim:

1. In an engine, a cylinder, a flange threaded to the cylinder, a head seated upon one end of the flange, a waterjacket having a bore at one end to receive the cylinder, and means for securing 20 the water jacket to the other end of the flange.

2. In an engine, a cylinder, a flange threadedly connected to the cylinder, a head seated upon one end of the flange, a water jacket having a bore in one end through which the cylinder extends and being in slidably engagement with the cylinder, packing means for preventing leakage 25 of water through the bore, and means for securing the water jacket to the other end of the flange.

3. In an engine, a cylinder, upper and lower 30 flanges threaded to the cylinder, a bed plate forming a seat for the lower flange to support the cylinder, a water jacket having a bore in one end to slidably receive the cylinder, packing means to

prevent leakage of water between the cooperating surfaces of the bore and the cylinder, and means for securing the other end of the water jacket to the upper flange.

4. In an engine, a cylinder having external threaded portions spaced along the length thereof, upper and lower flanges threaded on said portions, a bed plate forming a seat for the lower flange to support the cylinder, a water jacket having a bore in one end to slidably receive the cylinder, packing means in the water jacket to prevent leakage of water between the cooperating surfaces of the bore and the cylinder, and means for securing the other end of the water jacket to the upper flange. 80

5. In an engine, a cylinder, a water jacket disposed slidably on the cylinder and having inlet and outlet openings, and partition means dividing the water jacket into a plurality of compartments and having passages to convey water from one compartment to another, the passage in one partition means being staggered with respect to the passage in another partition to assure a spiral movement of the water through the water jacket. 85 90 95

6. In an engine, a cylinder having a plurality of threaded portions spaced with respect to each other on the exterior surface of the cylinder; a flange threadedly connected to one portion, a water jacket disposed about the cylinder, means for securing the water jacket to the flange, and a flange threaded on another threaded portion to form a seating surface for the cylinder. 100 105 110
